His Attorney.

UNITED STATES PATENT OFFICE

THOMAS A. E. BELT, OF SCHENECTADY, NEW YORK, ASSIGNOR TO GENERAL ELECTRIC COMPANY, A CORPORATION OF NEW YORK

LIGHT-SENSITIVE APPARATUS

Application filed August 6, 1928. Serial No. 297,396.

The present invention relates to light-sensitive apparatus and in particular to arrangements for controlling circuits in response to variations of light. When employing photo-electric cells or other forms of light-sensitive devices for actuating control circuits in response to changes in the intensity of a light source, it has been customary to employ several stages of amplification in order to derive sufficient output current. The presence of these amplifiers, particularly those of the thermionic type, renders the system somewhat complicated and to some degree unreliable from an operation standpoint. These disadvantages are accentuated in case the system is located in places which are either remote or otherwise not readily accessible, where tubes for replacement are not readily obtainable or where interruptions of the service are particularly objectionable, as in traffic signaling and the like. In accordance with one feature of the present invention, there is provided a high power amplifying circuit which is rendered operable by means of an electrical impulse derived from the light-sensitive apparatus or in some cases, by means of the lack of such impulse, to produce a current flow sufficient for operating directly a large current relay forming part of the circuit or circuits to be controlled, without the aid of additional amplification. Such control circuits have multifarious uses, for example, lighting signboards at dusk or energizing signal lights in response to the illumination of the photo-cell by the headlight of a moving vehicle. The improved system contemplates an amplifying device in which no filamentary or other fragile form of electron source is necessary although it is to be distinctly understood that my invention includes amplifiers and electron emitters of all kinds. According to another feature of my invention, the various apparatus employed is adapted to be energized directly by alternating current of ordinary voltage and frequency, thus facilitating their installation on existing lighting circuit lines. One of the objects of my invention is to provide a large current carrying circuit of simple and

rugged character which may be energized from an alternating current source and may be effectively controlled by a variable light source. Other objects and features will be apparent by reference to the specification taken in connection with the accompanying drawing which illustrates a preferred embodiment.

Referring to the figure, numeral 1 designates a transformer, the secondary of which consists of two portions or sections 2 and 3; the winding 2 provides energy for light-sensitive device 4 which may comprise a photo-cell of ordinary type, i. e., provided with a photo-sensitive cathode which is adapted to be activated by a light source (not shown). The circuit A contains in addition to the device 4, an output transformer 5 with adjustable taps to give any desired turn ratio, as shown. The winding 3 serves to energize an alternating current relay 6 and an ionization or arc device 7 which has in series therewith the secondary winding of transformer 5. The device 7 may comprise any of the well known cumulative ionization discharge apparatus which are characterized by a practically instantaneous collapse of impedance upon subjection to a potential greater than a predetermined value giving rise to an arc, or in some cases merely a glow discharge, with consequent rush of current. This apparatus conveniently may take the form of an envelope containing two electrodes immersed in a gas usually inert, e. g., helium, argon or the like, at a pressure ranging between 10 m. m. to 2 c. m. Hg, sufficient to support a glow or arc-like discharge depending upon the current requirements of the relay 6 and spaced apart a distance such that upon the application of suitable voltage, a discharge takes place in the manner stated. In the device as illustrated, the electrodes are of similar shape and size, hence substantially no rectification of the alternating current wave is produced although it is obvious that a rectifier may also be used to advantage in connection with a direct current relay. The respective circuits A and B are rendered electrically independent of one another except

for the coupling 5 by means of the equipotential conductor 8.

Upon the application of suitable voltage to the transformer 1, usually supplied from house lighting mains and assuming cell 4 to be inactivated, inappreciable current traverses the circuit 2, 4, 5, 8 because the impedance of the photo-cell is exceedingly high and hence comparatively no energy is transmitted through the coupling 5 to the adjacent circuit. Under these conditions, the voltage applied across the device 7 is so regulated as to preclude substantial discharge between the electrodes. This voltage ordinarily is maintained slightly below the voltage at which breakdown occurs. However, upon activation of the cell 4 by a light source, not shown which may comprise the head-light of a moving vehicle or a predetermined intensity of daylight or any other source, the changes of which are designed to initiate the controlling impulse, the photo-sensitive layer emits electrons and the impedance of the cell is greatly reduced, resulting in the application through the coupling 5 of an appreciable voltage upon circuit B. The additional voltage thus applied may be sufficient to initiate a substantial discharge i. e., glow or preferably an arc between the electrodes which discharge may persist during the remaining portion of the half cycle. A relatively large current is thus available for positively actuating the relay 6 which may control contacts forming portions of external circuits. The circuit A may be likened in a broad sense to a trigger arrangement so-called, in which a relatively small variation of energy originally produced by changes in the light source is adapted to effectively control, at least the initiation thereof, of a heavy current discharge in the adjacent circuit B. From the foregoing, it is evident that various modifications of the arrangement described will suggest themselves to those skilled in the art, for example, the photo-electric cell may be replaced by a selenium cell with suitable change in transformer voltages, also, the relay 6 may be designed to be actuated only when circuit A is de-energized as when the photo-cell 4 is in an inactivated state. Moreover, depending upon the function of the control circuits, energy derived through the coupling 5 from circuit A sometimes may be advantageously employed to detract from the energy normally flowing in circuit B in order to operate a differential relay.

What I claim as new and desire to secure by Letters Patent of the United States, is:—

1. Means for controlling a circuit in response to light variations, said means comprising a gaseous discharge device adapted to be substantially non-conductive at voltages below a predetermined voltage but to pass a discharge having arc-like characteristics above said voltage, an alternating current

source which normally applies a voltage across said device insufficient to cause a substantial discharge therethrough, and means including a light-sensitive device for increasing said voltage applied across said device sufficiently to cause an arc-like discharge to flow through said device thereby to energize the circuit to be controlled. 76

2. An electrical system comprising a source of alternating current connected to energize a plurality of circuits, one of said circuits containing a light-sensitive device and another of said circuits containing in series a cumulative ionization device, an electromagnetic relay and a member for coupling said latter circuit to the circuit containing the light-sensitive device, said member increasing the electrical energy in said latter circuit, upon activation of said light-sensitive device, by an energy transfer from said circuit containing the light-sensitive device. 75 80 85

3. In combination, a transformer having a multi-sectioned secondary, one of said sections being adapted to energize a circuit containing light-sensitive apparatus, another section being adapted to energize a circuit containing an electrical discharge device, said device being characterized by the fact that it is substantially conductive only at impressed voltages greater than a minimum and which normally is maintained at voltages less than said minimum and means whereby energy is transferred from the circuit containing the light-sensitive device, upon activation of the latter by light, to the other circuit for causing the electrical discharge device to be conductive. 90 95 100

4. In combination, a source of alternating current, a relay for controlling an auxiliary circuit and means serially connected between said source and relay for energizing the relay in response to changes in a light, said means comprising each of an electrical discharge device containing a pair of cooperating electrodes only, the space therebetween constituting relatively high impedance and of a light-sensitive device which upon activation by light cooperates with the electrical discharge device to reduce the impedance of the latter to a degree sufficient for the initiation of an arc discharge whereby the relay is energized. 105 110 115

5. In combination, a plurality of interconnected circuits, a common source of alternating current adapted to energize said circuits, one of said circuits containing light-sensitive apparatus and another containing a relay and an electrical discharge device in series, said device normally being of sufficiently high impedance to prevent the relay from operating but being adapted upon activation of the light-sensitive apparatus to have its impedance substantially reduced to an order sufficient to permit the initiation of a discharge having arc-like characteristics thereby to cause the actuation of said relay, and cou- 120 125 130

pling means, external to said electrical discharge device, for cooperating with said light-sensitive circuit and decreasing the impedance of said electrical discharge device.

In witness whereof I have hereto set my hand this third day of August, 1928.

THOMAS A. E. BELT.
